US0D1015105S

(12) **United States Design Patent** (10) **Patent No.:** **US D1,015,105 S**
(45) **Date of Patent:** **** Feb. 20, 2024**

(54) **NAIL GUN**

- (71) Applicant: **Zhejiang Prulde Electric Appliance Co., Ltd.**, Zhejiang (CN)
- (72) Inventor: **Weiming Yang**, Zhejiang (CN)
- (73) Assignee: **Zhejiang Prulde Electric Appliance Co., Ltd.**, Zhejiang (CN)

(**) Term: **15 Years**

(21) Appl. No.: **29/824,392**

(22) Filed: **Jan. 25, 2022**

(30) **Foreign Application Priority Data**

- Dec. 21, 2021 (CN) 202130844672.1

(57) **CLAIM**

The ornamental design for a nail gun, as shown and described.

DESCRIPTION

FIG. 1 is a top, front, and left side perspective view of a nail gun embodying my new design;

FIG. 2 is a bottom, rear, and right side perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken line portions of the nail gun in FIGS. 1-8 represent portions of the nail gun and form no part of the claimed design.

1 Claim, 8 Drawing Sheets
